UNITED STATES PATENT OFFICE.

CLARENCE KEMBLE BALDWIN AND THOMAS ROBINS, JR., OF NEW YORK,
N. Y., ASSIGNORS TO THE ROBINS CONVEYING BELT CO., A CORPORA-
TION OF NEW JERSEY.

CONVEYER.

No. 810,605.

Specification of Letters Patent.

Patented Jan. 23, 1906.

Application filed March 18, 1903. Serial No. 148,300.

To all whom it may concern:

Be it known that we, CLARENCE KEMBLE BALDWIN and THOMAS ROBINS, Jr., citizens of the United States, residing in the borough 5 of Manhattan, city, county, and State of New York, have invented certain new and useful Improvements in Conveyers, of which the following is a specification accompanied by drawings.

10 Our invention relates, broadly, to conveyers, but more particularly to portable conveyers of the type utilizing a continuously traveling conveyer-belt.

The objects of the invention are to improve upon the construction of portable conveyers and afford provision for moving the delivery end of the conveyer in all directions in a horizontal plane and also in a vertical plane.

20 Further objects of our invention are to enable the material to be delivered evenly and rapidly to the conveyer-belt when a belt is used without danger of damaging the belt and also to equalize the weight of the parts of the driving engine or motor on the frame of the apparatus.

25 Further objects of our invention will hereinafter appear; and to these ends our invention consists of apparatus for carrying out the above objects embodying the features of construction, combinations of elements, and arrangement of parts having the general mode of operation substantially as herein-after fully described and claimed in this specification and shown in the accompanying drawings, in which—

30 Figure 1 is a side elevation of one form of apparatus embodying our invention. Fig. 2 is a plan view of the same. Fig. 3 is an end view of the conveyer-frame and motor with the hopper removed. Fig. 4 is a transverse sectional view on the line 1 1 of Fig. 1 looking in the direction of the arrow. Fig. 5 is a side elevation of another form of the apparatus. Fig. 6 is a plan view of the same. Fig. 7 is a transverse sectional view on the line 5 5 of Fig. 5 looking in the direction of the arrow. Fig. 8 is an end view of the apparatus shown in Fig. 5. Fig. 9 is an enlarged detail side view of another form of shaking-chute. Fig. 10 is a partial plan view of Fig. 9. Fig. 11 is a transverse sectional view on the lines A B C D of Fig. 9. Fig. 12

is a side elevation, partly broken away, of a modified form of apparatus. Fig. 13 is a plan view of the same. Fig. 14 is a transverse sectional view of the apparatus shown in Fig. 12 on the line y y of Fig. 12, and Fig. 15 is a transverse sectional view on the line 13 13 of Fig. 13.

60 Referring to the drawings, in Fig. 1 the conveyer-frame A supports the idlers B and C, over which the continuously traveling conveyer-belt D runs, suitable means being provided for driving the belt, as the motor E, connected to operate the tail-pulley F, over which the belt D passes. At the opposite end of the belt a suitable take-up may be provided, and, as shown, a brush G is utilized for keeping the belt clean. According to our 70 invention the delivery end of the conveyer is movable in all directions in a horizontal plane. While various means may be provided for carrying out this object, according to the form of apparatus shown in Fig. 1 the frame A is bodily movable horizontally about a suitable pivot, and it may also be tipped in a vertical plane. As shown, the turn-table H is provided with a track I, bearing upon the rollers J, journaled in suitable bearings 80 upon the bed K. The turn-table H in this instance carries the frame L of the hopper O, and a pivot-pin P is interposed between the turn-table and the bed K to center the table. The conveyer-frame A is supported at its 85 outer end upon a swiveled roller Q, which may run upon the ground, while a bearing is afforded for the other end of the frame upon the rollers R, arranged upon the turn-table H.

According to the construction described it 90 will be seen that the outer end of the frame A, and with it the delivery end of the conveyer, may be swung in the horizontal plane through three hundred and sixty degrees, and it may also be raised up and down in the 95 vertical plane about the rollers R. Furthermore, the conveyer-frame may be moved in and out under the hopper O, the side channels S then rolling upon the rollers R, carried by the turn-table.

100 In Fig. 5 another form of apparatus is shown. In this instance the frame T for the hopper U is carried upon the conveyer-frame A, which in turn is pivoted about the axis V upon the turn-table W. In this construction the turn-table is provided with the roll-

ers X, running upon the track Y, and, as before, there is a pivot-pin Z for centering the table W. A swiveled roller a supports the outer portion of the frame A. According to 5 this construction the conveyer can make a full swing of three hundred and sixty degrees in a horizontal plane, and it can also be moved in a vertical plane around the axis V; but no provision is afforded for sliding it relatively to the table W, as in the construction 10 previously described in connection with Fig. 1. In Fig. 5 the conveyer-belt D is driven from a tail-drive by means of the tail-pulley b, and there is a snub-pulley c arranged at the 15 upper side of the belt, as described and claimed in the copending application of Clarence Kemble Baldwin, Serial No. 148,352, filed March 18, 1903.

The driving engine or motor may be placed 20 upon the ledge or extending portion d of the frame A, and in order to equalize the weight of the engine and its parts upon the frame the engine-shaft e is extended by means of the coupling f, and the fly-wheel g is placed 25 on the opposite side of the frame from the engine, thereby equalizing the weight on the turn-table. Suitable operative connections are interposed between the engine-shaft and the tail-pulley—as shown, a chain h connecting 30 the sprockets i for driving the conveyer-belt.

In combination with the continuously-traveling conveyer-belt we have shown some arrangements of shaking or reciprocating chutes for feeding the material to the belt, so constructed as to rapidly and uniformly feed the material and obviate all danger of damage to the belt by contact with the chute. Heretofore feeder-chutes have been hung at 40 both ends by rods or chains, with a driving-rod connected at either the back or front end, according to circumstances. The result is that the feeder-chute has a tendency to swing in a horizontal plane unless guided by some 45 suitable means, and this swinging is a great disadvantage when feeding a belt conveyer, owing to the liability of damaging the belt. There is also danger that the chains or rods carrying the front end of the chute will 50 stretch and allow the chute to come into contact with the belt. According to our construction the front or delivering end of the chute j is carried on a pair of wheels or rollers k, running on a short section of track l, so that the relative position between the end of 55 the chute and the belt is substantially constant. We do not necessarily limit ourselves to rollers running upon a track, as other suitable means may be provided for keeping the 60 relative position between the end of the chute and the belt substantially constant. The rear or receiving end of the chute j, as shown, is hung in this instance from the frame T by rods o, and provision is afforded 65 for raising and lowering the suspended end

of the chute j. The rods may be provided with adjusting-holes p for adjusting the height of the chute.

Suitable devices are provided for imparting a reciprocating or shaking motion to the 70 chute, as shown in this instance a disk crank q being journaled upon the frame A and provided with a connecting-rod pivoted to the axle of the wheels k under the chute. The disk crank q may be provided with apertures 75 r for varying the distance of the point of attachment of the connecting-rod s from the center of the disk crank, so that the length of the stroke may be varied. The disk crank q is connected to be driven by means of 80 the sprockets t and chain u from the tail-pulley shaft. By varying the angle of the chute the amount of material discharged per hour may be altered at will. According to our construction the back or suspended end 85 moves in the arc of a circle, while the front end moves in substantially a straight line, so that the material is drawn from the hopper during the forward portion of each stroke and the chute drawn from underneath the 90 material by the return stroke, thus allowing the material to fall freely to the belt. As hereinbefore described, according to our construction the front end of the feeder-chute is not permitted to swing in a horizontal plane, 95 and, moreover, the angle of the chute may be adjusted while the same is operating, as hereinafter to be described. The angle of the chute and extent of the throw may be varied at will. In Fig. 9 a different device is shown 100 for adjusting the angle of the chute, in this instance the back end of the chute being hung by the rods v and each rod being provided with a turnbuckle w. At the upper end of the buckles are sprocket-wheels connected by a chain y. At the other ends of the buckles are the hand-wheels z, so that by turning one hand-wheel the turnbuckle will be operated and both rods lengthened or 105 shortened to vary the angle of the chute. 110

In Fig. 12 a modified form of apparatus is shown which is applicable to both the constructions shown in Figs. 1 and 5. In Fig. 12 the outer end of the conveyer-frame is provided with a movable or hinged portion 1, so 115 constructed that when the main portion A' of the conveying apparatus is elevated at an angle in a vertical plane the hinged portion 1 may be adjusted to lie in a horizontal plane at a different angle from the main portion of 120 the frame. It is to be understood that the hinged frame 1 may be attached to the outer end of either of the constructions shown in Figs. 1 and 5. In Fig. 12 the portion 1 is shown hinged to a frame A' by way of illustration, in this instance the frame A' being provided with canvas decking 2, which is utilized to keep the material from dropping onto the return-belt, and by the use of canvas 125 also the weight is reduced. Of course suit- 130

able materials other than canvas may be utilized for the same object. In the construction shown in Figs. 1 and 5 sheet-iron deckings are provided. Suitable provision is afforded for supporting the frame A' in an inclined position, as desired—as shown, a portion of a chain 3, ring 4, and hook 5 being shown connected to a portion of the frame and the angle of the frame A' having been determined as desired the remaining portion 1 of the frame may be arranged in prolongation thereof or inclined at an angle thereto by adjusting the bolt 6. The frame A' is provided with the aperture 7, while the frame 1 is provided with the adjusting-holes 8. The frame 1 is pivoted to the frame A' at the point 9, and the holes 8 are upon the arc of a circle struck with the pivot-pin 9 as a center.

One of the important advantages of a construction such as shown in Fig. 12 resides in the fact that material may be delivered from a low elevation to a high elevation in a horizontal plane. One instance of the usefulness of the apparatus described is found in those cases where it is desired to deliver material from a dock to the deck of a vessel which stands at a considerably higher elevation than the dock, and many other instances may be found in which these or similar conditions are to be met.

In Figs. 13 and 15 it will also be seen that the fly-wheel 10 of the engine 11 has been removed and placed at the opposite side of the frame from the engine in order to equalize the weight. Another feature of the construction shown in these figures resides in the fact that the driving engine or motor 11 for operating the belt continuously instead of being placed at the tail end of the conveyer drives from the head end and is supported upon the hinged or jointed section 1 of the frame of the apparatus. As shown, the engine 11 is supported upon the frame or bracket 12 at one side of the frame 1. The fly-wheel 10 is supported on the other side of the frame 1, and suitable belt connections 13 operatively connect the engine-shaft 14 with the head-pulley 15 of the conveying-belt B.

Obviously some features of our invention may be used without others, and our invention may be embodied in widely-varying forms.

Therefore, without limiting ourselves to the construction shown and described nor enumerating equivalents, we claim, and desire to obtain by Letters Patent, the following:

1. The combination with a support, of a conveyer and conveyer-frame mounted to travel thereon, and having the delivery end of the conveyer both vertically and horizontally movable, and an engine or motor for operating the conveyer mounted upon the conveyer-frame, for substantially the purposes set forth.

2. The combination with a support, of a conveyer and conveyer-frame mounted to travel thereon, and having the delivery end of the conveyer movable in all directions in a horizontal plane, and an engine or motor for operating the conveyer mounted upon the conveyer-frame, for substantially the purposes set forth. 70

3. The combination with a turn-table, of a conveyer and conveyer-frame mounted for pivotal movement in relation to the turn-table, said conveyer and frame being capable of bodily travel also in a horizontal plane only over said table and transversely to the vertical axis thereof, for substantially the purposes set forth. 75

4. The combination with a turn-table, of a conveyer and conveyer-frame pivotally mounted relatively to the table, said conveyer and frame also being slidable transversely across the table, for substantially the purposes set forth. 80

5. The combination with a turn-table, of a hopper, a conveyer and conveyer-frame pivotally and slidably mounted relatively to the turn-table and hopper, for substantially the purposes set forth. 90

6. The combination with the turn-table, of a hopper, a conveyer and conveyer-frame pivotally and slidably mounted relatively to the turn-table and hopper, and an engine or motor for operating the conveyer mounted upon the conveyer-frame, for substantially the purposes set forth. 95

7. The combination with a continuously-traveling belt, of a hopper and a shaking feeder-chute, one end of which chute moves in substantially a horizontal plane, whereby the relative distance between the end of the chute and the traveling belt remains practically constant and injury to the belt is avoided, and means for reciprocating said chute, for substantially the purposes set forth. 100

8. The combination with a continuously-traveling belt, of a hopper and feeder-chute, 110 said chute being suspended to swing at one end and provided with rollers at the other end, a horizontal track for said rollers, and means for imparting a reciprocating motion to the said chute to feed the material to the belt, for substantially the purposes set forth. 115

9. The combination with a continuously-traveling belt, of a hopper and a shaking feeder-chute, one end of which is mounted to swing, and the other end of which is movable in substantially a horizontal plane, and means for preventing the chute from swinging sidewise, whereby injury to the belt is prevented, and means for imparting a reciprocating motion to the chute, for substantially the purposes set forth. 120

10. The combination with a continuously-traveling belt, of a hopper and a feeder-chute, one end of which is mounted to swing, and the other end of which is mounted to move in 125

substantially a horizontal plane, means for reciprocating said chute, and means for adjusting the angle of the chute, and means for varying the throw, for substantially the purposes set forth.

11. In a conveyer, the combination with a vertically-adjustable main frame, of a jointed section pivotally connected thereto, a conveyer carried by both said frames, and an engine or motor for operating the conveyer mounted upon said pivotally-connected section of the frame, for substantially the purposes set forth.

12. The combination with a shaking feeder-chute, of a swinging hanger therefor, and a substantially smooth track upon which the delivering end of the chute is supported and upon which the chute may be given a reciprocatory movement, for substantially the purposes set forth.

13. The combination with a shaking feeder-chute, of a swinging hanger near the receiving end of the chute, and a substantially smooth track upon which the delivering end of the chute is supported and upon which it is susceptible of reciprocatory movement, for substantially the purposes set forth.

14. The combination with a shaking feeder-chute, having its delivering end supported for reciprocatory movement in a horizontal plane, of a swinging support for the receiving end of the chute, and means for reciprocating the chute, for substantially the purposes set forth.

15. The combination with a shaking feeder-chute, of a conveyer to which said chute is adapted to deliver material, a swinging hanger for said chute, and supporting devices for the delivering end of said chute which permit the chute to be given a reciprocatory movement in a plane substantially

parallel to the conveyer, for substantially the purposes set forth.

16. The combination with a conveyer, of a shaking feeder-chute, a swinging support for the receiving end of the chute, a track substantially parallel with said conveyer upon which the delivering end of said chute is supported, and means for reciprocating the delivering end of said chute for substantially the purposes set forth.

17. The combination with a shaking feeder-chute, of swinging suspension devices for the receiving end of said chute, a substantially smooth track upon which the delivering end of said chute is supported, and means for reciprocating the delivering end of said chute along said track, said means being susceptible of adjustment to vary the throw of the chute, for substantially the purposes set forth.

18. The combination with a shaking feeder-chute set on an incline, of swinging suspension devices for the receiving end of said chute which are adjustable in length, and a substantially smooth track upon which the delivering end of said chute is supported and upon which it may be given a reciprocatory movement, for substantially the purposes set forth.

19. The combination with an inclined feeder-chute, of means for imparting oscillatory movement to its upper end, and means for imparting reciprocatory movement to its lower end.

In testimony whereof we have signed this specification in the presence of two subscribing witnesses.
